UNITED STATES PATENT OFFICE.

JAMES RAIT, OF NEWTON, MASSACHUSETTS.

DESIGN FOR A DISPLAY-STAND.

SPECIFICATION forming part of Design No. 24,927, dated November 26, 1895.

Application filed July 17, 1895. Serial No. 556,295. Term of patent 7 years.

To all whom it may concern:

Be it known that I, JAMES RAIT, a citizen of the United States, residing at Newton, in the county of Middlesex, State of Massachusetts, have invented and produced a new and original Design for Display-Stands, of which the following is a specification, reference being had to the accompanying drawing, forming part thereof.

10 The drawing herewith presented illustrates in a front elevation a display-stand embodying my design.

The essential features of my design comprise a vertically-disposed disk with arms circumferentially affixed to said disk, the whole supported upon a suitable base for the display of goods.

15 The particular features of my design consist in a polygonal disk or frame 2, which in-
20 closes a body portion in the form of a flat plate 3. Within the surface of the plate appears a ring 4, which is concentric with the circumference of the display-stand. The

edge of the disk 2 is surrounded with a border 5, having ornamentation in the form of a 25 "Greek" chain, so termed. Peripherally at intervals about the plate are radial studs 6 and arms 7, tangentially disposed. The plate 2 or frame is upheld by means of a circular base 8 with a pyramidal pedestal 9, the pe- 30 riphery of said pedestal comprising a num-
ber of facets 10, having a stippled surface with ornamental figures thereupon. The body of the base immediately below the ped- 35 estal is rounded or convex and contains or-
namentation in the shape of a Greek chain.

What I claim is—

The design for a display stand, as herein shown and described.

In testimony whereof I affix my signature 40 in presence of two witnesses.

JAMES RAIT.
